INVENTOR:

George D. Kayes,
BY Drake & Co., ATTYS.

UNITED STATES PATENT OFFICE.

GEORGE D. KAYES, OF ORANGE, NEW JERSEY.

BALANCING DEVICE FOR ROLLER-SKATERS.

SPECIFICATION forming part of Letters Patent No. 339,786, dated April 13, 1886.

Application filed November 18, 1885. Serial No. 183,175. (No model.)

To all whom it may concern:

Be it known that I, GEORGE D. KAYES, a citizen of the United States, residing at Orange, in the county of Essex and State of New Jersey, have invented certain new and useful Improvements in Balancing Devices for Roller-Skaters; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to balance a person learning to skate on rollers, and thus to avoid the expense heretofore incurred in hiring at the "rinks" young men as teachers for such persons.

20 The invention consists in the peculiar arrangements and combinations of parts, substantially as will be hereinafter set forth, and finally embodied in the clauses of the claims.

25 Referring to the accompanying drawings, in which like letters indicate corresponding parts in each of the figures, Figure 1 is a side elevation of a device embodying the invention. Fig. 2 is a bottom view thereof, to show the arrangement of the rollers and the brake adapted to 30 retard the motion of the skater when in the act of skating; and Fig. 3 is a detail section showing a preferred form of construction.

35 In said drawings, *a* is a body, made preferably of cast iron or bearing a heavy weight, which acts as a ballast to steady and support the skater. Said body is provided with rollers or wheels *b b*, to enable the said body to move freely over the floor with the skater. These are disposed at distances apart to give a broad 40 surface-bearing, whereby the skater is enabled to balance himself more perfectly. The weighted body is provided with a suitable socket, *c*, to receive a handle, *d d'*, by which the balancing device is operated, the said socket being 45 preferably on an incline, as shown, to throw a straight handle-rod, *d'*, back from the body *a*, so that the cross-bar *d* of said handle, or the vertical plane thereof, will be so far distant from the body as that the latter will not interfere with the movements of the skater.

50 In connection with the handled weight I

have provided a brake bar or rod, *e*, which extends from a point near the handle, where it may be easily operated by the hand resting on the handle-bar *d* through the body, and engages a spring-actuated friction piece or brake, *f*. This may be a block of rubber, *g*, fastened on the ends of a spring, *h*, which latter is in turn secured on the bottom of the body, as indicated in the drawings. The spring *p* coacts 60 with the spring *h* to hold the brake from the surface of the floor when the rod *e* is relieved of the pressure of the hand, though one or the other of said springs may be dispensed with.

65 In lieu of the arrangement shown, the friction-piece may be secured on the end of the rod *e*, or other changes may be made without departing from the spirit of the invention. Said rod *e* works in suitable bearings, *r r*, and 70 is preferably made in adjustable sections, whereby its length may be increased or diminished to suit the size of the skater. The handle, likewise, may be made adjustable either in the socket or by any suitable means 75 for the same purpose.

70 In providing bearings for the rollers I prefer to cast recesses *s* in the bottom of the body, in which the said rollers are secured by means of any suitable pins, *t*.

80 The operation of the device will be apparent. By placing the hands on the cross-bar *d*, the skater is steadied sufficiently to enable him to move forward with confidence, pushing the device before him. Gaining confidence 85 and practice, he is soon enabled to dispense with the balance and skate alone, having been taught without the expense of a teacher.

Having thus described the invention, what I claim as new is—

90 1. A balancing device for roller-skaters, combining therein a weighted body arranged on rollers, a handle, and a brake, said parts being arranged and adapted to operate substantially as herein set forth.

95 2. In combination, the weighted body carried by rollers, a handle to push the same forward, a brake actuated by a rod extending to a point near the hand-piece of said handle, and a spring to hold said brake from frictional contact, substantially as set forth.

100 3. In combination, the metal body *a*, pro-

- vided with wheels *b*, an inclined handle, and a brake having an actuating-bar extending to a point near the hand piece or portion of the handle, substantially as herein set forth.
- 5 4. In combination, in a balancing device for skaters, a weight, *a*, rollers *b*, socket *c*, handle-bar *d*, cross-bar *d*', braking-piece adapted to enter into frictional contact with the floor, and a rod, *e*, held in suitable bearings and adapted to depress said friction or braking piece, substantially as herein set forth.
5. In a balancing device for roller-skaters, the rod *e*, actuating the friction piece or brake and adapted to be lengthened or shortened to suit the size of the skater. ¹⁵
- In testimony that I claim the foregoing I have hereunto set my hand this 14th day of November, 1885.
- GEORGE D. KAYES.
